(57) **CLAIM**

The ornamental design for a connector for a device for distributing liquids, as shown and described.

DESCRIPTION

FIG. 1 is a perspective view of a connector for a device for distributing liquids according to our design;

FIG. 2 is a right side view of the connector of FIG. 1;

FIG. 3 is a left side view of the connector of FIG. 1 being opposite to the right side view;

FIG. 4 is a front view of the connector of FIG. 1;

FIG. 5 is a rear view of the connector of FIG. 1;

FIG. 6 is a top view of the connector of FIG. 1; and,

FIG. 7 is a bottom view of the connector of FIG. 1.

The broken lines in the drawings depict portions of the connector for a device for distributing liquids that form no part of the claimed design.
